REFINING VESSEL

Hans C. Glitsch, Dallas, Tex., assignor to Glitsch
Engineering Company, Dallas, Tex., a partnership

Application October 8, 1948, Serial No. 53,585

2 Claims. (Cl. 189—34)

1

This invention relates to new and useful improvements in trays for use in refining towers.

One object of the invention is to provide an improved tray for use in refining towers of various types and which is so constructed that a minimum quality of light-gauge material, such as stainless steel, may be utilized in fabricating the same without sacrificing its self-supporting characteristics.

Another object of the invention is to provide an improved refining tower tray having a plurality of deck plates or sections with their adjacent marginal edge portions frictionally clamped in overlapping relation, the underlying edge portion having a support made integral therewith for reinforcing its plate and said overlapping edge portions.

Another object of the invention is to provide an improved refining tower tray, of the character described, wherein the underlying plate margin has a depending flange forming an integral support for the adjacent plate margin, the overlying plate margin being upset to form an offset flange or shoulder which rests upon said underlying plate margin for supporting the main portion of its plate in substantially horizontal alignment with the plate having said underlying margin.

A construction designed to carry out the invention will be hereinafter described together with other features of the invention.

The invention will be more readily understood from a reading of the following specification and by reference to the accompanying drawings, wherein an example of the invention is shown and wherein:

Fig. 1 is a schematic plan view of a refining tower tray, constructed in accordance with the invention, shown mounted in a vessel.

Figs. 2 and 3 are views, similar to Fig. 1, showing modified arrangements of the deck plates,

Fig. 4 is a transverse, vertical, sectional view of the tray,

Fig. 5 is a perspective view, partly in section, showing the mounting of the deck plates of the tray,

Fig. 6 is a vertical, sectional view of the mounting,

Fig. 7 is a vertical, sectional view, showing the connection and relation of adjacent deck plates, and

Fig. 8 is a vertical, sectional view, showing another manner of frictionally fastening adjacent plate margins.

In the drawings, the numeral 10 designates the

cylindrical wall or shell of a refining tower or vessel which may be of any suitable or desired type, construction, diameter and height. For the purposes of illustration, the tower 10 has been shown as being of the bubble tower type; however, the usual risers and bubble caps have been omitted. The conventional refining tower includes a plurality of trays or decks A which extend transversely across the interior of said tower at spaced intervals substantially throughout the height thereof with the quantity and spacing of the trays being varied in accordance with the size and particular use of the tower. In view of the fact that the present invention relates particularly to the construction and mounting of the trays, only one tray has been shown and has been illustrated more or less diagrammatically and not in detail. The herein described construction may be successfully used in any refining vessel or tower having superimposed trays or decks and its use is not limited to the illustrated tower.

As is most clearly shown in Fig. 4, each tray A is supported within the tower by a substantially annular ring 11 which is welded or otherwise secured to the internal, cylindrical surface of the wall 10 which projects inward radially from said surface. A plurality of deck plates or floor sections 12, 13, 14, 15 and 16, of stainless steel or other suitable light-gauge and preferably corrosion-resistant material, have their end portions supported upon the ring, and frictionally fastened thereto by suitable clamps 17, such as shown in my United States Patent No. 2,341,091, issued February 8, 1944. The deck plates extend transversely of the tower in parallel relation with each section being relatively narrow in width compared to its length. Limited longitudinal movement of the plates, due to thermal expansion and contraction, is permitted by the frictional clamping of said plates to the ring. If desired, one or more beams or trusses 18, fabricated of stainless steel or other thin, light material, extend transversely of the deck plates of each tray for supporting said deck plates in cooperation with the ring. These beams or trusses are generally employed in tanks of large diameter or when heavy loads are imposed upon the trays. In vessels of small diameter, the beams or trusses 18 may be omitted as shown in Fig. 1. It is noted that the position and relation of the deck plates and beams to one another is subject to variation and that said plates may extend diagonally relative to said beams (Fig. 2), at right angles thereto (Fig. 3), or in any other desired relation.

Although not illustrated, the adjacent margins or end portions of the deck plates are adapted to be frictionally fastened to the beams by a plurality of clamps similar to the clamp 17. When employed, the ends of the beam 18 are secured by suitable brackets 19 to the wall 10 below the ring 11. One end of the tray terminates short of the wall 10 to provide an opening 20 for a weir type downcomer 21 which may be formed in sections and which preferably depends from and is secured to the free longitudinal margin of the deck plate 16. An effluent weir 22 is preferably formed along this plate margin by bending the same upwardly upon itself. It is noted that the major portion of the plate 12 overlies and is secured to the tank ring so as to underlie the downcomer (not shown) of the tray thereabove.

One of each of the adjacent longitudinal edge portions of the deck plates is upset to provide a parallel, co-extensive shoulder or flange 23 which overlies the margin of the adjacent deck plate (Figs. 5 and 7). A plurality of clamps 24 frictionally fasten together the adjacent margins or longitudinal edge portions of the plates and includes a bolt 25 extending through an opening 26 in the margin of the underlying plate. An angular clamping bar or member 27, having a depending leg or flange 28, is confined upon the bolt 25 so as to overlie the upset edge portion or flange 23 of the overlying plate and said bolt is engaged within a suitable nut 29 which is welded or otherwise secured in underlying relation to the opening 26. Due to the provision of the leg 28, the clamping member 27 extends parallel to the overlapping plate margin and draws said margin into snug frictional engagement upon tightening of the bolt 25. Although the plate margins are frictionally fastened together, the same may undergo limited lateral movement to compensate for thermal expansion and contraction due to temperature changes. If desired, a strip 30, of suitable packing material, may be interposed between the upset flange 23 and the underlying edge portion of the adjacent deck plate. It is noted that the major portions of the sections are substantially flat and that the spacing of the sections having the upset shoulders is greater than the width of the flat portions of said sections whereby said flat portions are spaced transversely from the underlying edge portions of adjacent sections (Fig. 7) and that the clamp bolts 25 and openings 26 are spaced transversely from said upset flanges. Thus, expansion joints are provided between adjacent sections.

For reinforcing and adding rigidity to the deck plates so as to eliminate the necessity of employing auxiliary supports, a depending leg or flange 31, may be formed by bending the underlying longitudinal edge portion of each leg downwardly upon itself at substantially a right angle. Additional rigidity may be obtained by bending the lower extremity of the leg 31 upwardly upon itself to provide a horizontal leg or flange 32. Also, an elongate flat member or bar 33 may be welded or otherwise secured to any of the depending flanges 31 so as to add stiffness thereto when load conditions are such as to require the same. This bar 33 is preferably formed of similar material, but is of heavier gauge or greater thickness. It is noted that the use of the stiffener bar and the horizontal leg of the depending flange is optional and is subject to variation in accordance with the length of the deck plate as well as the load imposed thereupon.

As shown in Fig. 4, the inner longitudinal edge

portion of the deck plate 12 is provided with the depending flange 31 and is overlapped by one of the upset flanges 23 of the plate 13. One longitudinal edge portion of the plate 14 is flanged and underlies the other upset flange of the plate 13, while its opposite edge portion is upset so as to overlie the adjacent edge portion of the plate 15. Both longitudinal edge portions of the latter are provided with the depending flanges 31 for supporting the adjacent overlying offset margins of the plates 14 and 15. Manifestly, this particular construction and arrangement of the deck plates is not essential or necessarily desirable, being subject to variation due to the location, strength and dimension of said plate as well as the load carried by the tray and its functions. In some installations, each plate will have only one depending flange and one upset flange.

For permitting the end portions of the deck plates to overlie the tank ring 11, the depending flanges 31 as well as their horizontal legs 32 are of less length than said plates so as to terminate short of said end portions as shown in Figs. 5 and 6. A clamp 34 is provided for frictionally fastening the connecting adjacent margins of the plates to the ring and includes an elongate, flat bar or clamping member 35 overlying and extending longitudinally of said adjacent margin. The plate 35 has an opening 36 for receiving the bolt 37 which extends through aligned openings 38 and 39 in the overlapping plate margins. An angular bar or clamping member 40, having an upstanding, transverse lug 41 at its inner end, underlies the ring 11 and is secured on the lower end of the bolt 37 by a suitable nut 42 with its lug bearing against the underside of the underlying plate margin. With the bars 35 and 40 of the clamp 34 aligned and fastened by the bolt 37 and its nut 42, it will be manifest that the adjacent margins may be frictionally clamped to the ring as shown in Fig. 6. It is noted that the end portions of the deck plates may be fastened to the tank ring in any suitable manner and that the particular form of the clamp 34 is subject to variation. In many instances, the clamps 17 are sufficient to connect the plates to the rings and sustain the weight of the tray as well as the load imposed thereupon. Ordinarily, the overlapping margins of the deck plates are fastened to the ring in the manner described only under heavy load or long span conditions.

If desired, a modified form of clamp or fastening device 43 may be used in place of the clamp 34. As shown in Fig. 8, the fastening device 43 includes a substantially flat hook or latch element 44 which is insertable through a slot 45 formed in the underlying deck plate adjacent the overlapping plate margins. The hook 44 is of general C-shape to provide an overhanging head or hanger portion 46 and an underlying bill 47. The upper surface of the latter is adapted to bear against the underside of the underlying plate margin. A flat, upright wedge element or locking key 48 is insertable in the head 46 which is bifurcated or split longitudinally for receiving the same and which has connected upstanding lugs 49 at its upper end for retaining the key. Suitable notches or recesses 50 are cut in the upper and lower surfaces of the key 48 adjacent its larger end to facilitate removal thereof. If desired, a shoulder 51 may be provided on the intermediate portion of the hook 44 for engaging the upper surface of the underlying plate and limiting downward movement of said hook. Upon insertion of the key 48, its

lower edge portion bears against and overlies the upset flange 23 whereby the overlapping plate margins are clamped between said key and the bill 47 of the hook. A substantially identical clamp or fastening device is shown in my co-pending application, Serial No. 698,143, filed September 20, 1946.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A refining vessel tray including, a plurality of elongate deck sections of light gauge metal incapable of absorbing thermal stresses, the sections being supported at their ends and disposed with their longitudinal edge portions in adjacent substantially parallel relationship, said sections having major flat portions, an upset horizontal flange on one of the longitudinal edge portions of adjacent sections overlying and resting upon the edge portion of the other section, and integral flange depending from the underlying edge portion for reinforcing its section and providing a support therefor and for the upset horizontal flange, and frictional fasteners car-

ried by each deck section adjacent its underlying edge portion in transversely spaced relation to said upset flange and overlying said flange to clamp the same against upward displacement relative to said underlying edge portion, the sections having the upset flanges being spaced from adjacent sections a distance greater than the width of their flat portions whereby said flat portions are spaced transversely from the underlying edge portions of adjacent sections, whereby lateral thermal expansion and contraction of adjacent sections is permitted.

10 2. A refining vessel tray as set forth in claim 1 including replaceable packing removably confined between the upset flange of one section and the underlying edge portion of the adjacent section.

HANS C. GLITSCH.
